CHAIN OR SIMILAR ARTICLE

Joseph Sternberg, New York, N. Y.

Application September 27, 1949, Serial No. 5,195

Term of patent 14 years

(Cl. D45—16)

To all whom it may concern:

Be it known that I, Joseph Sternberg, a citizen of no country, residing in New York city, county of New York, and State of New York, have invented a new, original, and ornamental Design for a Chain or Similar Article, of which the following is a specification, references being had to the accompanying drawing, forming part thereof, wherein,

I claim:

The ornamental design for a chain or similar article, substantially as shown.

JOSEPH STERNBERG.
